UNITED STATES PATENT OFFICE.

HUGH THOMAS BRASELL, OF FORT SUMNER, NEW MEXICO.

ADJUSTABLE SPLINT.

Application filed June 13, 1922. Serial No. 567,985.

To all whom it may concern:

Be it known that I, HUGH T. BRASELL, a citizen of the United States, residing at Fort Sumner, in the county of De Baca and State 5 of New Mexico, have invented certain new and useful Improvements in Adjustable Splints, of which the following is a specification.

This invention relates to improvements in 10 surgical splints and more particularly to a splint designed for employment in connection with the lower limbs, and the primary object of the invention is to provide a splint by the use of which the inconvenience and 15 disadvantages of confining the broken limb in a plaster of Paris cast are obviated.

Another object of the invention is to provide a splint which, while it will be adapted to properly sustain the broken or fractured 20 limb in as efficient a manner as though encased in a cast, will permit of convenient access at all times to the injured member for the purpose of treatment.

Another object of the invention is to provide a splint so constructed as to cause minimum inconvenience to the patient and much less discomfort than a plaster cast.

A further object of the invention is to provide a splint which may be adjusted and 30 adapted to the broken or fractured limb in a manner to insure of proper setting of the bones and without the liability of any subsequent deformities.

A still further object of the invention is 35 to provide a splint which will be as effective as a plaster cast in sustaining the injured limb in condition to insure of proper setting of the bones and which will yet be of such construction as not to interfere with 40 the patient moving about on crutches and otherwise assisting himself, which is not practical where a cast is employed.

In the accompanying drawings:

Figure 1 is a perspective view of the splint 45 embodying the invention;

Fig. 2 is a vertical transverse sectional view therethrough;

Fig. 3 is a horizontal sectional view on the 50 line 3—3 of Fig. 2 looking in the direction indicated by the arrows;

Fig. 4 is a view partly in side elevation and partly in vertical section illustrating the foot rest of the appliance;

Fig. 5 is a perspective view of the supporting member for the foot rest.

Generally speaking, the splint embodying the invention comprises a frame embodying means for securing it in proper position upon the injured limb and adjustable to meet the conditions, and a foot rest adjustably mounted within the frame and in the drawings the said frame is indicated in general by the numeral 1 and comprises an upper section and a lower section indicated in general, respectively, by the numerals 2 and 3. 60 The upper section 2 of the frame comprises side members 4 which preferably extend parallel to each other and may be of rod material, and these members are connected at their upper ends by an arcuate yoke portion 65 5 adapted to extend about the rear side of the limb in the applied position of the splint.

The numeral 6 indicates a limb encircling band which is preferably relatively broad and which may be made of leather or any other material found suitable for the purpose, and this band is disposed within the upper edge portion of the frame, as best shown in Figs. 1, 2 and 3 of the drawings, and has its upper rear marginal portion riveted or otherwise secured, as at 7, to the yoke member 5. The band 6 is open at its front, as indicated by the numeral 8, so as to adapt it to be applied about the limb as, for example, at a point immediately below the knee, as shown 75 in Fig. 1, and a lacing string 9 is suitably adjusted through eyelets 10 provided at the opposite sides of the open front 8 of the band and may be drawn and tied so as to secure the band about the limb with a sufficient degree of snugness and firmness to retain the appliance in proper position. Preferably a flap 11 of cloth, leather, or any other flexible material suitable for the purpose, is secured to the inner side of the band at one 80 side of the open front 8 and is adapted to be arranged about the forward side of the limb and in a position extending across the open front 8. This flap serves to obviate any discomfort which might otherwise be caused 90 to the patient through the presence of the open front 8 and lacing string 9. At this point 95 it will be evident that the yoke member 5 encircles the rear side of the band 6 and that the upper portions of the side members 4 100 extend downwardly at opposite sides of the said band and, when the band is applied to the limb, are, as a consequence, positioned at opposite sides of the lower portion of the limb.

110

The frame section 3 comprises side members 12 and a cross bar 13 connecting the lower ends of said members. The side members 12 are of tubular form and telescopically receive the lower end portions of the side members 4 of the frame section 2, as best illustrated in Fig. 2, set screws 14 being threaded through bosses 15 formed at the upper ends of said members 12 and being adapted to be tightened so as to bind against the members 4 and thus secure the two sections of the frame in positions of relative longitudinal adjustment. It will be evident by reference to Fig. 1, that the side members 12 of the frame section 3 likewise extend at opposite sides of the limb, and the cross bar 13 extends transversely beneath the foot, in the applied position of the splint.

20 The foot rest embodies in its structure a cross bar or head 16 provided in its ends with openings 17 receiving the side members 12 of the frame section 3 and adapting the said member to be adjusted vertically within the frame. The cross bar 16 is provided with a standard 18 which projects downwardly from its underside at a point substantially mid-way between its ends and extends adjustably through an opening 19 formed in the mid-portion of the cross bar 13. This portion of the standard is threaded, as indicated by the numeral 20, and an adjusting nut 21 is fitted onto the standard and bears against the cross bar 13. It will now be evident that by adjusting the nut 21 the standard 18 will be adjusted vertically through the opening 19 and the cross bar 16 will be correspondingly adjusted vertically within the frame. A short standard 22 projects upwardly from the upper side of the cross bar 16 preferably in alignment with the lower standard 18 and is provided with a spherical head or ball 23 which serves a purpose to be presently explained.

25 The foot rest further includes a foot plate 24 provided upon its underside with a downwardly projecting short shank 25 constituting an extension from a socket 26, the wall of which is split vertically, as at 27, to provide segments 28 adapted to fit snugly about the head 23 of the standard 22. The shank 25 is gradually increased in diameter exteriorly as it merges with the 30 socket 26, and it is also exteriorly threaded, as indicated by the numeral 29. A nut or threaded collar 30 is fitted on to the threaded shank 25 and may be threaded down upon the shank so as to close the segments 28 about the head 23 with a greater or less degree of firmness. It will be understood at this point that the socket 26 will fit the head 23 in a manner to afford a substantially universal joint connection between the foot plate 24 and standard 22

so that the foot plate may be adjusted to assume any desired angular position calculated to most comfortably and properly support the foot. Any suitable cushioning surface or padding material 31 may be applied upon the upper side of the foot plate 24.

From the foregoing description of the invention it will be obvious that the splint constructed as described may be readily adapted to a broken or fractured limb and its several component parts suitably relatively adjusted to conform to the length of the limb and the desired angular disposition of the foot. It will also be seen that while the splint is designed to maintain the injured limb in the position which it is desirable it shall assume during the knitting process, it is not liable to cause any discomfort inasmuch as it is not cumbersome, does not encase the limb, and is so light in weight as not to impose any appreciable strain on the muscles.

It will be understood that while the splint in the form illustrated in the drawings is designed more especially for application to a broken or fractured lower limb, the principles of the invention may be made use of in the production of a splint for use upon the upper limbs. It will also be evident that considered in a general way, the splint embodies a frame, means associated therewith for attaching the same to a limb, and a rest within the frame for an articulated member of the limb and which member would be the foot of the lower limb or the hand of an upper limb.

Having thus described the invention, what is claimed as new is:

A surgical splint comprising a frame member including side bars and a yoke connecting said bars at one end, a limb-encircling band secured rigidly to said yoke and disposed between said side bars, a second frame member including tubular side bars and a cross bar connecting said side bars at one end, the side bars of the first-mentioned frame member being adjustably secured in the tubular side bars of the second frame member, a crosshead slidably engaged at its ends upon the tubular side bars, a standard fixed to and extending from one side of said crosshead through the cross bar of the second-mentioned frame member, adjustable means for securing said standard in the cross bar, a second standard fixed to and extending from the opposite side of the crosshead and terminating in a ball, a rest member provided on one side with a shank terminating in a split socket adapted to fit around said ball, and means for clamping said socket about the ball.

In testimony whereof I affix my signature.

HUGH THOMAS BRASELL.
